ABSTRACT OF THE DISCLOSURE

Fungicidal compositions comprising an inert fungicidal adjuvant and a fungicidally effective amount of the compound of the formula

This invention relates to α -substituted sulfonium ylids and to processes for their preparation. This invention further relates to fungicidal compositions and to methods for the control of fungal organisms.

This application is a division or copending application Ser. No. 549,160 filed May 11, 1966, now abandoned.

The sulfonium ylids of this invention are represented by the formula

wherein R and R¹ are each selected from the group consisting of hydrogen, alkyl of not more than 12 carbon atoms and haloalkyl of not more than 12 carbon atoms containing 1, 2 or 3 halogen atoms (Cl, Br, F and I). R² is selected from the group consisting of halogen (Cl, Br, F and I) and alkyl of not more than 4 carbon atoms, R³ is selected from the group consisting of NO₂ and alkoxy of not more than 4 carbon atoms, R⁴ in phenyl, a is an integer from 0 to 5 inclusive, b is an integer from 0 to 2 inclusive, c is an integer from 0 to 1, and Y is selected from the group consisting of

and

wherein R⁵ is alkyl of not more than 4 carbon atoms, R⁶ and R⁴ are each selected from the group consisting of alkyl of not more than 4 carbon atoms, alkenyl of not more than 4 carbon atoms and phenyl, X and X¹ are halogen (Cl, Br, F and I) and s and t are integers from 0 to 5 inclusive, R⁸ is selected from the group consisting of alkyl of not more than 4 carbon atoms and halogen (Cl, Br, F and I), R⁹ is NO₂, n is an integer from 0 to 3 inclusive and m is an integer from 0 to 2 inclusive.

In the above formula the alkyl of R and R¹ can be, for example, methyl, ethyl, n-propyl, isopropyl, n-butyl, sec-butyl, isobutyl, tert-butyl, amyl, hexyl, heptyl, octyl, nonyl, decyl, dodecyl and the various homologues and

isomers of alkyl having from 1 to 12 carbon atoms, and the haloalkyl of R and R¹ can be, for example, chloromethyl, iodomethyl, bromomethyl, fluoromethyl, trichloromethyl, tribromomethyl, chloroethyl, iodoethyl, bromoethyl, fluoroethyl, dichloroethyl, chloro-n-propyl, bromo-n-propyl, iodoisopropyl, bromo-n-butyl, bromo-tert-butyl, 1,3,3-trichlorobutyl, 1,3,3-tribromobutyl, chloropentyl, bromopentyl, 2,3-dichloropentyl, 3,3-dibromopentyl chlorohexyl, bromohexyl, 2,4-dichlorohexyl, 1,3-dibromohexyl, 1,3,4-trichlorohexyl, chloroheptyl, bromoheptyl, fluoroheptyl, 1,3-dichloroheptyl, 1,4,4-trichloroheptyl, 2,4-dichloromethylheptyl, chlorooctyl, bromooctyl, iodoctyl, 2,4-dichloromethylhexyl, 2,4-dichlorooctyl, 2,4,4-trichloromethylpentyl, 1,3,5-tribromoocetyl and the halogenated straight and branched chain nonyl, decyl, undecyl and dodecyl.

As alkyl, R², R⁵, R⁶, R⁷ and R⁸ each can be methyl, ethyl, n-propyl, isopropyl, n-butyl, isobutyl, sec-butyl and tert-butyl. As alkoxy, R³ can be methoxy, ethoxy, n-propoxy, isopropoxy, n-butoxy, sec-butoxy, isobutoxy, and tert-butoxy.

The α -substituted sulfonium ylids of this invention are prepared by a process which comprises reacting a sulfonium ylid of the formula

30 with a compound selected from the group consisting of

wherein R, R¹, R², R³, R⁴, R⁶, R⁹, X, a, b, c, n and m are as defined above, and Z is selected from the group consisting of R⁵ OR⁵, and

45 wherein R⁵, R⁶, R⁷, X, X¹, s and t are as defined above.

When reactant (A) above is used the process can be represented by the following representative synthesis:

60 wherein Z is as defined above.

The process utilizing reactant (A) is carried out by reacting substantially 2 molar equivalents of sulfonium ylid with one molar equivalent of the substituted-carbonyl chloride compound in the presence of an inert organic medium at a temperature in the range of about 0° C. to about 60° C. However, higher or lower temperatures can be used, the temperature not being critical. Pressure is likewise not a critical factor in the process of this invention employing reactant (A). Pressure both above and below atmospheric pressure can be employed, although atmospheric pressure is preferred for convenience.

Illustrative substituted-carbonyl chloride compounds useful in the preparation of the sulfonium ylids of this invention include:

methoxyalyl chloride
ethoxalyl chloride
propoxaylyl chloride
sec-butoxaylyl chloride
(methcarbonyl)carbonyl chloride
(ethylcarbonyl)carbonyl chloride
(isopropylcarbonyl)carbonyl chloride
(sec-butylcarbonyl)carbonyl chloride
(tert-butylcarbonyl)carbonyl chloride
N,N-dimethylcarbamoylcarbonyl chloride
N,N-diethylcarbamoylcarbonyl chloride
N,N-dibutylcarbamoylcarbonyl chloride
N,N-di(tert-butyl)carbamoylcarbonyl chloride
N,N-dichloromethylcarbamoylcarbonyl chloride
N,N-di(2-chloroethyl)carbamoylcarbonyl chloride
N,N-di(2-chlorobutyl)carbamoylcarbonyl chloride
N,N-di(2-fluoropropyl)carbamoylcarbonyl chloride
N-methyl-N-ethylcarbamoylcarbonyl chloride
N,N-divinylcarbamoylcarbonyl chloride
N,N-diallylcarbamoylcarbonyl chloride
N,N-di(2-butene-1-yl)carbamoylcarbonyl chloride
N,N-di(2-bromopropen-1-yl)carbamoylcarbonyl chloride
N,N-diphenylcarbamoylcarbonyl chloride

When reactant (B) above is used the process can be represented by the following representative synthesis:

The process utilizing reactant (B) is preferably carried out with substantially equimolar amounts of reactants, although a small excess of either can be used, in the presence of an inert organic medium. Reaction temperature and pressure are not critical and temperatures and pressures disclosed above for the process utilizing reactant (A) are suitable.

Illustrative isocyanates useful in the preparation of the sulfonium ylids of this invention include:

phenyl isocyanate
2,4-dimethylphenyl isocyanate
2,4,6-trimethylphenyl isocyanate
3,5-dimethylphenyl isocyanate
4-methylphenyl isocyanate
4-tert-butylphenyl isocyanate
3,5-diethylphenyl isocyanate
2-methylphenyl isocyanate
6-methylphenyl isocyanate
6-tert-butylphenyl isocyanate
3,5-di-n-propylphenyl isocyanate
2,6-dimethylphenyl isocyanate
2-methyl-6-nitrophenyl isocyanate
4-chlorophenyl isocyanate
2,4-dichlorophenyl isocyanate
2,4,6-trichlorophenyl isocyanate
2,4,6-tribromophenyl isocyanate
3,5-diodophenyl isocyanate
2,6-difluorophenyl isocyanate
3,5-dichlorophenyl isocyanate
2,6-dichlorophenyl isocyanate
2-chlorophenyl isocyanate
4-bromophenyl isocyanate
2,6-dibromophenyl isocyanate

2-chloro-4-nitrophenyl isocyanate
4-nitrophenyl isocyanate
6-nitrophenyl isocyanate
2,4-dinitrophenyl isocyanate
5 2,6-dinitrophenyl isocyanate
3,5-dinitrophenyl isocyanate

Inert organic media which can be used in the process of this invention utilizing either reactant (A) or reactant (B) include, for example, hydrocarbons such as benzene, toluene, xylene, cyclohexane, methylcyclohexane, n-heptane, n-hexane and the like and organic halides such as carbon tetrachloride, n-butylchloride, ethylenedichloride, chlorobenzene and the like.

The separation of the resulting reaction product from the reaction mixture is readily accomplished. The solvent can be removed by stripping or distillation, preferably low temperature vacuum distillation. The product if desired can be purified by any of the conventional means well-known in the art, selective extraction, recrystallization or any suitable combination of these methods.

The α -substituted sulfonium ylids of this invention are crystalline solid materials which are insoluble in water but somewhat soluble in many organic solvents, for example alcohols, ketones, hydrocarbons such as benzene, toluene, xylene and the like and chlorohydrocarbons such as chlorobenzene carbon tetrachloride and the like.

The sulfonium ylids used as starting materials in the preparation of the α -substituted sulfonium ylids of the invention are prepared by the process disclosed in K. W. Ratts et al., Stable Sulfonium Ylids, J. Org. Chem. 31, 1885-1188 (1966). Said comprises reacting a sulfonium salt of the formula

40 with a substantially equimolar amount of an alkaline material such as sodium hydride in the presence of an inert liquid media such as tetrahydrofuran, where R, R¹, R², R³, R⁴, a, b, c and X are as defined above.

The following examples illustrate the invention. Parts and percent are by weight unless otherwise indicated.

EXAMPLE 1

50 A suitable reaction vessel is charged with a solution of 4.5 parts of dimethylsulfonium 4'-nitrophenacylide in 70 ml. of methylene chloride and then a solution of 4.7 parts of 3,4-dichlorophenyl isocyanate in methylene chloride is added dropwise over a period of a few minutes. The reaction mixture is filtered to recover the solids which are crystallized from methylene chloride to give 6.9 parts of dimethylsulfonium-2-[(3',4' - dichlorophenyl) carbamoyl]-4'-nitrophenacylide. M.P. 223-229° C. The product is confirmed by infrared spectrum analysis.

55 Calc'd for C₁₇H₁₄Cl₂N₂O₄S (percent): C, 49.40; H, 3.41; Cl, 17.16; N, 6.78; O, 15.49; S, 7.76. Found (percent): C, 49.65; H, 3.65; Cl, 16.89; N, 6.77; O, 15.31; S, 7.73.

EXAMPLE 2

60 A suitable reaction vessel is charged with about 4.5 parts of dimethylsulfonium 4'-nitrophenacylide, 50 parts of benzene and 10 parts of methylene chloride. A solution of about 1.4 parts of ethoxalyl chloride in 15 parts methyl alcohol is then added dropwise to the reaction vessel over a 5 minute period with stirring at about 50° C. The reaction mixture is filtered to remove the solids (3.8 parts) which are then extracted with benzene. The benzene extract is concentrated under vacuum to give 1.0 part of yellow solid. The filtrate from the reaction mixture is concentrated under vacuum to give 1 part of an orange solid. The orange solid and yellow solid are combined and recrystallized twice from benzene to give 1.5 parts of di-

methylsulfonium - 2 - [(ethoxycarbonyl)carbonyl] - 4' - nitrophenacylide, M.P. 164-164.5° C.

Calc'd. for $C_{14}H_{15}NO_6S$ (percent): C, 61.68; H, 4.65; N, 4.31; S, 9.86. Found (percent): C, 52.15; H, 4.51; N, 4.87; S, 9.99.

Following substantially the same procedure as in the foregoing examples the following compounds of this invention are prepared.

Example:

- 3.----- Dimethylsulfonium-2-(phenylcarbamoyl)phenacylide.
- 4.----- Dimethylsulfonium-2-[(3',5'-dibromophenyl)carbamoyl]-4'-chlorophenacylide.
- 5.----- Dimethylsulfonium-2-(4'-iodophenylcarbamoyl)-4'-methoxyphenacylide.
- 6.----- Dimethylsulfonium-2-(4'-methylphenylcarbamoyl)-2',4'-dimethoxyphenacylide.
- 7.----- Dimethylsulfonium-2-[(2',4'-dimethylphenyl)carbamoyl]-4'-phenylphenacylide.
- 8.----- Dimethylsulfonium-2-[(2',4',6'-trimethylphenyl)carbamoyl]-4'-phenylphenacylide.
- 9.----- Dimethylsulfonium-2-(p-ethylphenylcarbamoyl)-2',4'-dichlorophenacylide.
- 10.---- Dimethylsulfonium-2-(m-methylphenylcarbamoyl)-2',4'-dibromophenacylide.
- 11.---- Dimethylsulfonium-2-(m-tert-butylphenylcarbamoyl)-2',4'-dimethylphenacylide.
- 12.---- Dimethylsulfonium-2-[2',6'-di(tert-butyl)phenylcarbamoyl]-2'-methylphenacylide.
- 13.---- Dimethylsulfonium-2-(m-fluorophenylcarbamoyl)-4'-methylphenacylide.
- 14.---- Dimethylsulfonium-2-[(2',4'-dinitrophenyl)carbamoyl]-4'-ethylphenacylide.
- 15.---- Dimethylsulfonium-2-(p-nitrophenylcarbamoyl)phenacylide.
- 16.---- Dimethylsulfonium-2-(2'-methyl-4'-nitrophenyl)carbamoylphenacylide.
- 17.---- Dimethylsulfonium-2-(2'-chloro-4'-nitrophenyl)carbamoyl-4'-methylphenacylide.
- 18.---- Dimethylsulfonium-2-[(2',4',6'-trichlorophenyl)carbamoyl]phenacylide.
- 19.---- Dimethylsulfonium-2-[(N,N-dimethylcarbamoyl)carbonyl]-2',4'-diethoxyphenylphenacylide.
- 20.---- Dimethylsulfonium-2-[(N,N-dimethylcarbamoyl)carbonyl]-2',4'-dichlorophenylphenacylide.
- 21.---- Dimethylsulfonium-2-[(N,N-divinylcarbamoyl)carbonyl]phenacylide.
- 22.---- Dimethylsulfonium-2-[(N,N-dipropylcarbamoyl)carbonyl]-4'-methylphenylphenacylide.
- 23.---- Dimethylsulfonium-2-[N,N-di(chloromethyl)carbamoyl]phenacylide.
- 24.---- Dimethylsulfonium-2-[(N,N-di-2-chlorobutylcarbamoyl)carbonyl]-2',4'-dichlorophenylphenacylide.
- 25.---- Dimethylsulfonium-2-[(N,N-di-3-chlorobut-1-ylcarbamoyl)carbonyl]phenacylide.
- 26.---- Dimethylsulfonium-2-[(N,N-diphenylcarbamoyl)carbonyl]phenacylide.
- 27.---- Dimethylsulfonium-2-[(N,N-di[2',4'-dichlorophenyl]carbamoyl)carbonyl]phenacylide.
- 28.---- Dimethylsulfonium-2-[(N,N-di[2',4',6'-tribromophenyl]carbamoyl)carbonyl]phenacylide.
- 29.---- Dimethylsulfonium-2-[(N,N-di[p-fluorophenyl]carbamoyl)carbonyl]phenacylide.
- 30.---- Dimethylsulfonium-2-[(methoxycarbonyl)carbonyl]phenacylide.
- 31.---- Dimethylsulfonium-2-[(ethoxycarbonyl)carbonyl]-4'-methylphenacylide.
- 32.---- Dimethylsulfonium-2-[(propoxycarbonyl)carbonyl]-2',4'-dichlorophenacylide.
- 33.---- Dimethylsulfonium-2-[(methylcarbonyl)carbonyl]-4'-nitrophenacylide.
- 34.---- Dimethylsulfonium-2-[(n-butylcarbonyl)carbonyl]-4'-methoxyphenacylide.
- 35.---- Dimethylsulfonium-2-[(methoxycarbonyl)carbonyl]-2'-tert-butylphenacylide.
- 36.---- Dimethylsulfonium-2-[(2',4'-dimethylphenyl)carbamoyl]-2',4',6'-trichlorophenacylide.
- 37.---- Di(2-chloroethyl)sulfonium-2-[(propylcarbonyl)carbonyl]phenacylide.
- 38.---- Methylethylsulfonium-2-[(ethoxycarbonyl)carbonyl]-2',4',6'-trimethylphenacylide.
- 39.---- Dimethylsulfonium-2-[(3',4'-dichlorophenyl)carbamoyl]-2',4'-dichlorophenacylide.
- 40.---- Dimethylsulfonium-2-[(N,N-dimethylcarbamoyl)carbonyl]-4'-tert-butylphenacylide.

The α -substituted sulfonium ylids of this invention are useful as pesticides, particularly fungicides. In practicing the present α -substituted sulfonium ylids is applied to the fungal organisms or the material to be treated for the control of fungi in an amount sufficient to exert fungicidal activity. The fungicidal ylids of this invention are particularly effective when applied directly to the soil for control of soil borne fungal organisms. They are also effective in the treatment of plant life such as vegetables, ornamental plants and fruit-bearing trees; organic fibers and fabrics; leather; paints and lubricating oils and various cellulosic materials such as wood. In application to soil and plants, fungicidal control is obtained in most instances

by the application of about 0.01 pound to about 25 pounds of active ingredient per acre. The preferred amount is determined by and dependent upon the particular fungicidal ylid selected, the method of application, and in the case of application to plant life, the state and condition of growth and the climatic conditions.

The effectiveness of the compounds of this invention as fungicides is illustrated below.

Slide germination test: The concentration of active ingredient required to substantially inhibit germination of spores from 7- to 10-day old cultures of *Venturia inaequalis* is determined by the slide germination test. A concentrated formulation of 1.0 gram of dimethylsulfonium - 2 - [(ethoxycarbonyl)carbonyl] - 4' - nitrophenacylide, acetone and 0.1 gram of sorbitan monolaurate polyoxyethylene derivative (a commercial water-soluble non-ionic emulsifying agent) is prepared. This concentrated formulation is diluted with sufficient water to provide an aqueous emulsion containing 10 p.p.m. of the nitrophenacylide. To a test tube is then added four volumes of the aqueous emulsion, one volume of spore stimulant and one volume of spore suspension, the spore stimulant being added to insure a high and relatively stable percentage of germination of the control. Drops of the test specimen mixture and an untreated control are pipetted onto glass slides. The glass slides are then placed in moist chambers for 20 hours incubation at 22° C. Germination counts are made by counting 100 potentially viable spores, i.e. spores which would germinate under the normal conditions of the control. It was found that the fungicide nitrophenacylide substantially inhibited germination of the spores whereas the control spores completely germinated.

In a similar evaluation against the late blight fungus *Phytophthora infestans* at a concentration of 10 p.p.m., dimethylsulfonium - 2 - [(ethoxycarbonyl)carbonyl]4'-nitrophenacylide substantially prevented germination of spores of said fungus.

The fungicidal compositions of this invention contain at least one active ingredient and a material referred to in the art as a fungicidal adjuvant in liquid or solid form. The fungicidal compositions are prepared by admixing the active ingredient with an adjuvant including diluents, extenders, carriers and conditioning agents to provide compositions in the form of finely-divided particulate solids, granules, pellets, aerosols, solutions, dispersions or emulsions. Thus the active ingredient can be used with an adjuvant such as a finely-divided particulate solid, a liquid or organic origin, water, a wetting agent, dispersing agent, an emulsifying agent or any suitable combination of these.

Typical finely-divided solid carriers and extenders which can be used in the fungicidal compositions of this invention include for example, the talcs, clays, pumice, silica, diatomaceous earth, quart, Fuller's earth, salt, sulfur, powdered cork, cottonseed hulls, powdered wood, walnut flour, chalk, carcoal, tobacco dust, volcanic ash, wheat flour, soybean flour, tripoli, redwood flour, and the like. Typical liquid diluents include for example, water, kerosene, Stoddard solvent, hexane, benzene, toluene, acetone, ethylene dichloride, xylene, alcohols, diesel oil, glycols and the like. Typical diluents for aerosols include, for example, Freons such as dichlorodifluoromethane, trichlorofluoromethane, and the like.

The fungicidal compositions of this invention, particularly liquids and wettable particles, usually contain as a conditioning agent one or more surface-active agents in amounts sufficient to render a given composition readily dispersible in water or in oil. By the term "surface-active agent" it is understood that wetting-agents, dispersing agents, suspending agents, emulsifying agents and the like are included therein.

The surface-active agents employed can be of the anionic, cationic or nonionic type. They include, for example, sodium oleate, sulfonated petroleum oils, alkyl aryl sulfonates, sodium lauryl sulfate, polyethylene oxides, lignin sulfonates, and other surface-active agents.

The fungicidal compositions of this invention generally contain from about 0.005% to about 95% by weight of the active fungicidal ingredient.

The active compounds of the present invention can be employed in combination with other fungicides to give compositions that have broad spectrum fungicidal activity. In these mixtures, the auxiliary fungicidally active materials can be present in any desired amount, ordinarily from about 0.1 to about 20 parts by weight per one part by weight of α -substituted sulfonium ylid of the present invention. In some instances it may even be desirable to employ two or more auxiliary fungicides.

Typical of the auxiliary fungicides that can be employed in combination with the α -substituted sulfonium ylids of the present invention are the following:

N-trichloro-methylthio-4-cyclohexene-1,2-dicarboximide
Tetramethylthiuram disulfide
Manganese ethylene-bis-dithiocarbamate
Ferric dimethyl dithiocarbamate
Zinc ethylene-bis-dithiocarbamate
Zinc dimethyl dithiocarbamate
Tetra copper calcium oxychloride
Tetrachloro-p-benoquinone
2,3-dichloro-1,4-naphthoquinone
2-dichloro-6-(o-chloroanilino)triazine
Ethylene thiuram monosulfide
2-heptadecyl glyoxalidine acetate
Ferric dimethyl dithiocarbamate plus 2-mercaptopbenzo-thiazole
Manganese dimethyl dithiocarbamate plus 2-mercaptopbenzothiazole
Copper dihydrazinium sulfate
Copper-S-quinolinolate
Cycloheximide
Terramycin
Streptomycin

When operating in accordance with the present invention, the α -substituted sulfonium ylids or a composition containing them can be applied to the fungal organisms to be controlled, or to their habitats in any convenient

fashion, e.g. by means of hand dusters or sprayers. Applications to the above-ground portions of plants conveniently can be carried out with powder dusters, boom sprayers and spray dusters. In foliar applications, the employed compositions should not contain any appreciable amount of phytotoxic diluents. In large scale operations, dusts or low volume sprays can be applied from airplanes.

The term "fungicidal composition" as used herein and in the appended claims is intended to mean not only compositions in a suitable form for application but also concentrated compositions which require dilution or extension with a suitable quantity of liquid or solid adjuvant prior to application.

Although the invention is described with respect to specific modifications, the details thereof are not to be construed as limitations except to the extent indicated in the following claims.

The embodiments of the invention in which an exclusive property or privilege is claimed are defined as follows:

1. A fungicidal composition comprising an inert fungicidal adjuvant and a fungicidally effective amount of the compound of the formula

30 2. A method for control of fungal organisms which comprises applying to the fungus infested area a fungicidally effective amount of the compound of the formula
